BOILER

Charles T. Denker and John R. Moore, Chicago,
Ill., assignors to The Calefactor Corporation,
Chicago, Ill., a corporation of Illinois

Application March 27, 1947, Serial No. 737,650

2 Claims. (Cl. 122—348)

1

This invention relates to boilers and more specifically to boilers of the water tube-fire tube type.

It is a primary object of our invention to afford an efficient and novel boiler wherein the combustion products and the water flowing therethrough are brought into intimate heat exchange relationship with each other.

Another object of our invention is to afford a novel fire tube-water tube boiler wherein the hot combustion gases pass successively over the outside of the water tubes and through the water tubes.

Another object of our invention is to construct a water tube-fire tube boiler in such a manner that the hot combustion gases, in flowing to the fire tubes from the combustion chamber in which they are formed during operation of our boiler, flow both transversely to, and counter to, the direction of flow of the water in the water tubes in good heat exchange relationship therewith.

A further object of our invention is to afford a water tube-fire tube boiler wherein the water flows both longitudinally and transversely thereof.

Yet another object of our invention is to afford a water tube-fire tube boiler wherein the water tubes are arranged in rows in spaced apart relation to each other with the water tubes in the outer rows spaced closer together than the tubes in the inner rows so that the water tubes in the rows adjacent to the side walls thereof form water walls for the boiler.

Another object of our invention is to associate the heat-exchange elements thereof with each other in a novel and expeditious manner whereby the fire-tubes may be of relatively small diameter.

A further object of our invention is to construct a novel water tube-fire tube boiler wherein the air used to support combustion of the fuel therein is pre-heated by passing downwardly through passageways formed in the walls of the boiler.

Other and further objects of the present invention will be apparent from the following description and claims and are illustrated in the accompanying drawings which, by way of illustration, show a preferred embodiment of the present invention and the principles thereof and what we now consider to be the best mode in which we have contemplated applying these principles. Other embodiments of the invention embodying the same or equivalent principles may be used and structural changes may be made as de-

2

sired by those skilled in the art without departing from the present invention and the purview of the appended claims.

In the drawings:

Fig. 1 is an end elevational view, partly in section, of a boiler embodying the principles of our invention;

Fig. 2 is a sectional view taken substantially along the line 2—2 in Fig. 1;

Fig. 3 is a detail sectional view taken substantially along the line 3—3 in Fig. 1;

Fig. 4 is a sectional view taken substantially along the line 4—4 in Fig. 1; and

Fig. 5 is an enlarged detail sectional view of part of the structure shown in Fig. 1.

The boiler shown in Figs. 1 to 5 of the accompanying drawings comprises a housing 20 mounted on a supporting table 22.

The housing 20 comprises two side walls 24 and 25, two end walls 27 and 28, a top wall 30 and a bottom wall 31. Each of the side walls 24 and 25, the end walls 27 and 28, the top wall 30 and the bottom wall 31 of the housing 20

comprises an inner panel 33 and an outer panel 34. These panels may be made of any suitable material such as, for example, sheet steel and, as is best seen in Figs. 1 and 4, the center portion of the inner panel 33 of the bottom wall 31 is eliminated and a sheet of a suitable refractory material R, such as, for example, fire-brick, is mounted on this portion of the outer panel 34 thereof for a purpose which will be more apparent hereinafter.

Suitable insulating material, such as, for example, sheets of magnesia material M are positioned between the inner panel 33 and the outer panel 34 of the side walls 24 and 25, the end walls 27 and 28 and the bottom wall 31. The insulating material M positioned between the inner panels 33 and the outer panels 34 of the side walls 24 and 25 and the bottom wall 31 fill the space therebetween. No insulating material M is positioned between the inner panel 33 and the outer panel 34 of the top wall 30, the panels

33 and 34 thereof being spaced apart to form an air passageway 35, as will be discussed in greater detail hereinafter. The sheets of insulating material M between the inner panels 33 and outer panels 34 of the end walls 27 and 28 are spaced

50 from the outer panel 34 thereof to form air passages 36 and 37 through the end walls 27 and 28, respectively, which are in communication with the air passage 35 through the top wall 30.

The table 22 comprises a casing 39 mounted on a supporting frame 41. The lower end por-

tions of the outer panels 34 of the end walls 27 and 28 of the housing 20 extend downwardly therefrom and form end walls 27a and 28a for the casing 39 which are connected to a bottom wall 43 and two side walls 45 and 46 thereof to form an air chamber C which is in communication with the air passages 36 and 37. The supporting frame 41 comprises two bracing members 48 mounted on four legs 49; the bottom wall 43 of the casing 39 resting on the bracing members 48 and the bottom wall 31 of the housing 20 resting on the upper end portions of the legs 49.

As is best seen in Fig. 4, an exhaust stack or chimney 51 having an inner shell 53 and an outer shell 54, which are spaced apart to define an air passage 56, is mounted on the top wall 30 with the outer shell 54 in sealed relation to the outer panel 34 thereof and the inner shell 53 in sealed relation to the inner panel 33 thereof so that the air passage 56 is in communication with the air passage 35. The upper end portion of the air passage 56 is open to the atmosphere so that, during the operation of our boiler, air may be drawn down through the passageways 56, 35, 36 and 37 into the air chamber C from whence it may be fed into the housing 20 to support the combustion of fuel therein as will be discussed in greater detail hereinafter.

As is best seen in Fig. 1, the side walls 24 and 25 slant outwardly toward their bottoms to thereby provide two wings W₁ and W₂ within which are mounted two banks B₁ and B₂ of water tubes 58.

The water tubes 58 in the bank B₁ are mounted therein in three rows X, Y and Z, which are substantially parallel to the side wall 24, and the water tubes 58 in the other bank B₂ are similarly mounted in three rows X', Y' and Z', which are substantially parallel to the side wall 25. The lower ends of the water tubes 58 in the rows X, Y, Z, X', Y' and Z' are sealed into water headers 61, 62, 63, 61', 62' and 63', respectively, carried by the end walls 27 and 28. The upper ends of the water tubes 58 in the rows X, Y and Z are sealed into one compartment 65 of an upper header 66, and the upper ends of the water tubes 58 in the rows X', Y' and Z' are sealed into the other compartment 65' thereof, the top and bottom walls of the upper header 66 being braced by suitable members such as stay bolts 67. The upper header 66 is carried by the side walls 24 and 25 and the end walls 27 and 28, the two compartments 65 and 65' thereof abutting each other and being fastened together by any suitable means such as welding. However, it will be understood that the two-compartment upper header 66 is shown merely to illustrate our invention and not by way of limitation thereto, and that other forms of upper headers, such as, for example, one continuous header to which the upper end portions of all the water tubes 58 are connected, may be used without departing from the purview of our invention. The upper header 66 divides the housing 20 into an upper combustion chamber U and a lower combustion chamber or fire-box F as will be discussed in greater detail herein-after.

A plurality of fire tubes 68 extend between, and through, the water headers 61, 62, 63, 61', 62' and 63' and the upper header 66, each of the fire tubes 68 extending longitudinally through a corresponding one of the water tubes 58 in spaced relation to the sidewalls thereof.

An inlet manifold 70 is connected by nipples

11, 72, 73, 74, 75 and 76 to water headers 61, 62, 63, 61', 62' and 63', respectively, for feeding water into the water headers, and an inlet pipe 78 is connected to the inlet manifold 70. During the operation of our boiler, water or other working fluid is fed from a suitable source of supply through the inlet pipe 78 into the inlet manifold 70, and from there through the nipples 71-76 into the water headers 61-63 and 61'-63' from whence it passes through the water tubes 58 into the upper header 66. A pipe 79 having bifurcations 81 and 82 connected to the compartments 65 and 65' of the upper header 66 affords a conduit for discharging hot water or other working fluid from the header 66 of our boiler during operation thereof.

Although our novel boiler is readily adapted for use with various types of fuels, for the purpose of illustrating our invention it is shown in the accompanying drawings as embodying a plurality of gas burners 84 mounted in the bottom wall 31 and projecting upwardly therefrom in two parallel rows of three burners each. The burners 84 are connected to a box manifold 86 attached to the lower surface of the center portion of the bottom wall 31 of the housing 20.

A mixture of gas and air may be fed to the manifold 86, and thus to the burners 84 by any one of several units adapted for this purpose and which are well known in the art, the unit shown in the accompanying drawings comprising a mixing chamber 88 connected to the manifold 86 by a coupling member 90; a blower 92 connected to the mixing chamber 88 for feeding air thereto; and a feed line 94, including a pipe 96; a valve 97 and a pipe 98, through which fuel gas may be fed from a suitable source of supply into the mixing chamber 88. The fuel gas fed through the feed line 94 into the mixing chamber 88 intimately mixes with the air fed thereto by the blower 92, and then passes through the manifold 86 and the burners 84 into the fire-box F wherein it is ignited and burned.

As is best seen in Figs. 2 and 3, the water tubes 58 in each of the two banks B₁ and B₂ are spaced progressively closer together from the inside rows X and X' to the outside rows Z and Z'. Thus for example, as is best seen in Fig. 3, in the row X, eight water tubes 58 are spaced equal distances apart along the length of the water header 61; in the row Y, nine water tubes 58, of the same size as those in the row X, are spaced equal distances apart along the length of the water header 62 and are, therefore, closer together than the water tubes 58 in the row X; and in the row Z, ten water tubes 58, of the same size as those in both the rows X and Y, are spaced equal distances apart along the length of the water header 63 and are, therefore, positioned closer together than the water tubes 58 in either the row X or the row Y. The water tubes 58 in the rows X', Y' and Z' in the bank B₂ are positioned in substantially the same relation to each other as the water tubes 58 in the rows X, Y and Z, respectively. It will be seen that with this construction although good circulation of the hot gases and other combustion products, resulting from the combustion of the fuel gas fed by the burners 84 into the fire-box F, is afforded through the two banks B₁ and B₂ of water tubes as a whole, the progressively closer spacing of the water tubes 58 toward the side walls 24 and 25 of the housing 20 shields these walls from the high temperatures of these hot gases while affording an effective heat ex-

change element for heating the water or other working fluid passing through the boiler.

Operation

In the operation of our novel boiler, air enters the air chamber C through the air passages 56, 35, 36 and 37 and is blown by the blower 92 into the mixing chamber 88 where it is mixed with fuel gas fed from a suitable supply source through the pipe 98, the control valve 97, and the pipe 96. The mixture of air and fuel gas is fed from the mixing chamber 88 through the coupling 90 into the box manifold 86 from whence it is discharged through the burners 84 into the firebox F where it is ignited between the two banks B₁ and B₂ of water tubes 58.

The hot gases and other combustion products resulting from the combustion of the mixture of fuel and air discharged from the burners 84 circulate within the firebox F between the water tubes 58 in each of the rows X, Y, Z, X', Y' and Z', and pass downwardly between and around the water headers 61, 62, 63, 61', 62' and 63' into the lower end portion of the wings W₁ and W₂ where they enter the lower end portions of the fire tubes 68 and pass upwardly therethrough into the upper combustion chamber U from whence they are discharged to the atmosphere through the stack 51.

The boiler water or other working fluid, which is to be heated in our boiler during the operation thereof, is, of course, fed through the inlet manifold 70 into the water headers 61-63 and 61'-63' and passes therefrom upwardly through the water tubes 58 into the upper header 66 from whence the hot water or other working fluid, produced by the heat of the gases passing through the boiler, is exhausted through the pipe 79.

The circulation of hot combustion products within the firebox F of our novel boiler, in heat exchange relation with the lower side of the upper header 66 and the outer surface of the water tubes 58, is considerably different than most boilers heretofore known to the art inasmuch as it substantially reverses on itself in flowing therethrough. Thus it will be noted that the hot combustion products formed in the area surrounding the burners 84 tend to rise upwardly across the water tubes 58 to the upper part of the firebox F where, because of the baffle effect of the lower surface of the water header 66 and because of the draft of our boiler, they are deflected downwardly and caused to swirl back down between the water tubes 58 toward the bottom of the wings W₁ and W₂ where they enter the lower end of the fire tubes 68 and pass upwardly therethrough into the upper combustion chamber U and from there pass through the stack 51 to the atmosphere. Thus it will be seen that the combustion products are caused to hover somewhat within the firebox F in good heat exchange relationship with the upper header 66, the water tubes 58 and the water headers 61-63 and 61'-63' so that a relatively large percentage of the heat of the hot combustion products has been transferred to the boiler water before the combustion products enter the fire tubes 68. Because of this, the temperature of the combustion products is somewhat reduced before entering the fire tubes 68 which tends to cause the combustion products to contract so that relatively small fire tubes are enabled to handle the volume of combustion products flowing from the firebox F.

Also it will be noted that another advantage

of my novel boiler is that the higher temperature combustion products within the firebox F, exteriorly of the water tubes 58, are in good heat exchange relation with the higher temperature working fluid, namely, the working fluid within the upper header 66 and the upper end portions of the fire tubes 68 so that a relatively great temperature differential is maintained therebetween which thereby affords continued efficient heating of the higher temperature working fluid.

Also, it will be seen that the combustion products in flowing through the firebox F to the lower end of the fire tubes 68 pass across the water headers 61-63 and 61'-63' in good heat exchange relationship therewith and affords good pre-heating of the water therein before it enters the water tubes 58.

From the foregoing, it will be apparent that we have provided a novel fire tube-water tube boiler wherein the water in the water tubes thereof is efficiently heated from both the outside and the inside, the water in the water headers is efficiently pre-heated before entering the water tubes, and wherein the working fluid in the upper header is efficiently heated by high temperature combustion products.

Also it will be seen that we have provided a novel fire tube-water tube boiler wherein the hot gases and other combustion products resulting from the combustion of fuel therein pass successively along and around the outer surface of the water tubes, in good heat exchange relationship with the water tubes and the upper header, and then through the fire tubes into the upper combustion chamber and through the stack to the atmosphere.

Furthermore it will be noted that we have afforded a novel boiler wherein the water tubes are positioned in rows therein in such a manner that good circulation of hot combustion gases is afforded therebetween, and the outer rows of water tubes afford relatively good heat shields for the side walls of the boiler.

Also, it will be noted that we have provided a novel boiler wherein the hot gases pass over the outside surface of the water tubes in a generally opposite direction to the flow of working fluid therethrough so that the warmer gases on the outside of the water tubes are in good heat exchange relationship with the warmer working fluid therein and thereby are effective to efficiently raise the temperature of the working fluid to a high level.

In addition, it will be noted that we have afforded a novel boiler which may be readily converted to either a steam boiler or a hot-water boiler with a minimum change in construction.

Hence, while we have illustrated and described the preferred embodiments of our invention, it is to be understood that these are capable of variation and modification and we therefore do not wish to be limited to the precise details set forth, but desire to avail ourselves of such changes and alterations as fall within the purview of the following claims.

We claim:

1. A boiler of the character described and comprising a housing including side walls and end walls connected together, a plurality of water tubes mounted in said housing in a plurality of substantially parallel rows and having upper and lower ends, said rows and said water tubes being substantially parallel to the closest of said side walls of said housing, said water tubes in the rows adjacent to said side walls being positioned

closer together than said water tubes in the rows further from said side walls, fire tubes mounted in said water tubes, a header connected to the upper end portion of said water tubes in communication therewith, header means mounted in said housing and connected to the lower end of said water tubes for introducing water into said water tubes, means for feeding fuel into said housing for combustion therein, means for exhausting combustion products from said housing, said last named means comprising means, including said fire tubes and said water tubes, for providing a passage for the combustion products successively over the outside surface of said water tubes, downwardly through said header means and longitudinally through said fire tubes.

2. In a boiler of the character described, a housing comprising a top wall, a bottom wall, two end walls, and two side walls, each of said side walls slanting outwardly toward the bottom, two banks of water tubes mounted within said housing, each of said banks being mounted in said housing adjacent to a corresponding one of said side walls and each comprising a plurality of said water tubes arranged in substantially parallel rows, said water tubes in each of said rows being mounted in spaced relation to each other and being substantially parallel to each other and to said corresponding one of said side walls, certain of said rows of water tubes in each of said banks being closer to the corresponding one of said side walls than other of said rows in said bank, the water tubes in said rows in each of said banks which are closer than other rows in that bank being closer together than the water tubes in the last mentioned rows, a header connected to the upper end portions of said water tubes in said housing, said header forming an imperforate partition wall exteriorly of said water tubes dividing said housing into a lower chamber and an upper chamber, water headers mount-
